UNITED STATES PATENT OFFICE.

CALVIN D. FARRIER, OF PLAINVILLE, KANSAS.

PIPE PULLER.

Application filed May 1, 1924. Serial No. 710,393.

To all whom it may concern:

Be it known that I, CALVIN D. FARRIER, a citizen of the United States, residing at Plainville, in the county of Rooks and State 5 of Kansas, have invented certain new and useful Improvements in Pipe Pullers, of which the following is a specification, reference being had therein to the accompanying drawings.

10 This invention relates to pipe and rod pullers for pumps and has special reference to devices which are adapted to be easily lowered into engagement with pipes or rods and then positively engage the pipes or rods 15 for lifting the same from the well or well cylinder.

One object of this invention is the production of a pipe or rod puller which is so formed as to be provided with a pivotally 20 mounted cap, this cap being adapted to be swung so as to allow the pipe or rod to pass through the puller and then fall into a binding engagement with the pipe or rod for causing the same to be easily lifted upon 25 the lifting of the puller.

Another object of this invention is the production of a pipe and rod puller having a pivotally supported cap for facilitating the engagement of a rod or pipe, this cap 30 being provided with a simple and efficient means for adjusting the size of a cut-away portion formed therein for accommodating different sized pipes or rods.

With these and other objects, this invention 35 consists of certain novel combinations, constructions, and arrangements of parts as will be hereinafter fully described and claimed.

In the accompanying drawing:

40 Figure 1 is a detailed perspective view of the pipe or rod puller, illustrating the manner in which the same is used.

Figure 2 is a central vertical section through the device, showing the same in 45 operation.

Figure 3 is a top plan view of the pipe or rod puller, portions of the device being shown in section.

Figure 4 is a section taken on the line 4—4 50 of Figure 3.

Figure 5 is a bottom plan view of the cap.

Referring to the accompanying drawings 55 by numerals, it will be seen that 1 designates a collar which is carried by the lower ends of the arms 2 comprising the yoke 3. The

arms 2 extend into the collar 1 and are welded in engagement therewith so as to form a substantial one-piece structure, after the device has been assembled. One of the 60 arms 2 is provided with a squared portion 4, adjacent the collar 1, for purposes to be hereinafter set forth.

It will be seen by referring to Figure 2 that the collar 1 tapers towards its lower 65 end as indicated at 5 for facilitating the passing of the collar 1 over the upper end of the pipe 6. Therefore when the pipe or rod 6 is carried within the well cylinder 7 or within a well, the puller may be easily 70 lowered over the pipe or rod inasmuch as the taping of the collar 5 will constitute a guide for causing the puller to be easily passed over the upper end of the pipe or rod. The yoke 3 also comprises in combination with the arms 2 the loop 8 to which the ring 9 is attached for the purpose of 75 allowing the lifting cable 10 to be easily secured thereto whereby the puller may be raised and lowered by the use of the cable 10. 80

The cap 11 which is used in connection with this puller, is substantially round so as to conform to the shape of the upper portions of the collar 1. This cap 11 has the enlarged integral pivot lugs 12 formed upon 85 its rear portion and at a spaced distance apart. These lugs 12 are adapted to embrace the side portions of the squared portion 4 of one of the arms 2 and to be secured in position by means of the pivot pin 13. By 90 this construction it will be seen that the cap will be positively secured in position and will be allowed to freely swing as the occasion requires. The cap 11 is beveled as shown at 14 so as to allow the same to swing 95 upwardly when necessary without interference from the squared portion 4 of one of the arms. This cap is provided with a V-shaped notch 15 formed in alignment with the lugs 12 but upon the opposite periphery of the cap. The eye 16 is fixed upon the cap 11 and the operating cable 17 is passed through this eye so as to be secured thereto whereby, upon the operation of this cable 17 the cap may be raised or lowered as desired. 100

In order to accommodate different sized pipes or rods, there is provided a plate 18 which is pivotally secured to the upper portion of the cap 11 by means of the pivot bolt 19. The opposite end of the plate 18 is 110 also secured by the adjusting bolt 20 which is adapted to pass through one of the aper-

tures 21 for retaining the plate in an adjusted set position. It will be noted that these apertures 21 are formed in alinement so as to easily accommodate the adjusting bolt 20 and therefore when the plate is 5 swung to different positions and is held in a desired position by means of the bolt, the size of the cut-out portion 15 may be increased or diminished. By referring particularly to Figure 3, it will be seen that in 10 full lines the plate is shown as extending to provide a size of opening through which medium sized pipes or rods may be passed, but in dotted lines the plate is shown swung 15 to a position for accommodating large sized pipes or rods.

When this device is in use, the collar 1 will pass over the upper portion of the pipe or rod and owing to the pressure of the rod 20 or pipe upon the lower portions of the cap 11, the cap will swing upwardly. As soon as the upper portion of the pipe has passed the cap, the cable 10 may be drawn upwardly so as to lift the pipe or rod puller. 25 This action will cause the cap 11 to positively bind in engagement with the pipe or rod and therefore the pipe or rod may be drawn from the well or well cylinder. As hereinbefore set forth, the size of the opening 30 formed by the cut-away portion may be increased or diminished by the operation of the plate 18 and therefore this device is capable of being used in connection with any sort of a well for lifting the pipes and 35 rods therefrom.

What I claim is:

1. In a pipe and rod puller for wells, the combination of a collar, means for lifting said collar, a cap pivotally mounted upon 40 the upper end of said collar, said cap provided with a notched portion, said cap being adapted to be moved upwardly for facilitating the passing of a rod or pipe through said collar, at which time said cap will fall

into engagement with said pipe or rod for 45 causing the rod to rest within said notch, and means for increasing or diminishing the size of the opening caused by said notch, whereby various sized pipes or rods may be accommodated. 50

2. In a pipe and rod puller for wells, the combination of a collar, a cap pivotally mounted upon the upper portions of said collar, said cap provided with a notched portion thereby forming an opening, said collar being adapted to be passed over the upper portions of a rod or pipe, at which time the cap will be swung upwardly for allowing the upper portions of a pipe or rod to pass thereby, said cap then being adapted 60 to swing into a binding engagement with the pipe or rod, a plate pivotally mounted upon said cap, adjacent said notched portion, said cap provided with a plurality of apertures, an adjusting bolt passing through 65 one of said apertures and through said plate, for positively retaining the plate in an adjusted set position, thereby increasing or diminishing the size of the opening formed by said notched portion, whereby 70 various sized pipes or rods may be accommodated when it is desired to lift the same. 75

3. In a pipe and rod puller for wells, the combination of a collar, a cap pivotally mounted upon said collar, said cap provided with a notched portion, said collar being adapted to pass over the upper end of a pipe or rod for allowing the pipe or rod to pass through the notched portion of said cap, and a plate adjustably mounted upon said cap 80 adjacent said notched portion for increasing or diminishing the size of the opening formed by said notched portion, whereby various sized pipes or rods may be accommodated, when it is desired to lift the same. 85

In testimony whereof I hereunto affix my signature.

CALVIN D. FARRIER.
